WORK-DRIVING DOG.

1,191,113.

Specification of Letters Patent.

Patented July 11, 1916.

Application filed March 18, 1916. Serial No. 85,175.

To all whom it may concern:

Be it known that I, SALMON W. PUTNAM, 3d, a citizen of the United States, residing at Fitchburg, in the county of 5 Worcester and State of Massachusetts, have invented certain new and useful Improvements in Work-Driving Dogs, of which the following is a specification.

My invention relates to certain new and 10 useful improvements in driving-dogs particularly designed for use in turning the steel tires of locomotive driving-wheels, coach-wheels, truck-wheels and all other wheels employing a steel or other tire, the turning 15 being performed while the wheels are mounted upon their axles. Lathes of this type are well known, and it is usual in performing the turning operation to mount the axle, with its wheels, on the centers of a 20 double-head driving-wheel lathe, such lathes commonly presenting a face-plate contiguous to the outer face of each driving-wheel when mounted upon the axle, as before mentioned. By suitable mechanism the two face 25 plates are driven in unison.

The object of my invention is to equip such a lathe as mentioned, or any other style of turning lathe, or different kinds of face-plates or table work on both the usual 30 form of so-called engine lathe, and boring or turning mills, etc., with a novel driving-dog which may be applied with little or no modification, to form a positive and effective driver which is equalizing, and capable 35 of adjusting itself automatically to the load, or in other words to the resistance offered by the cutting tool.

With the foregoing and other objects in view, my invention consists of the parts and 40 the constructions and combinations of parts which I will hereinafter describe and claim.

In the accompanying drawing forming part of this specification and in which similar reference characters indicate like parts in 45 the several views; Figure 1 is a longitudinal sectional view of a driving dog embodying my invention. Fig. 2 is a front view of the same. Fig. 3 is an end view.

The driving dog which I am about to 50 describe is designed primarily, as before stated, for use in connection with steel-tired-lathes and driving-wheel-lathes, and which lathes usually contain a head-stock and a tail-stock with face-plates between

which the axle with its wheels will extend, 55 said head-stock and tail-stock being usually provided with internal spindle-carrying centers having means of adjustment longitudinally, and the driving-dogs being usually adjustably secured in slots formed in 60 the face-plates, but these features form no part of the present invention and hence are not illustrated.

In carrying out my present invention I 65 form the dog of a base-member or jaw-holder, 10, having lugs, 11, through which pass bolts, 11', by which the jaw-holder is secured to and outstands from the face of the face-plate, the bolts being adapted for 70 slidable operation in the usual radial channels or slots formed in the face-plate and being capable of adjustment radially from the usual spindle-carrying centers, and said jaw holder having a tongue, 10', which in actual operation, extends into a T-slot in 75 the face-plate forming a means of positive drive and relieving the bolts which hold the driving-dog to the face-plate of the lathe, from all driving strains.

At the outer end, the jaw holder is channeled as at 12 to receive and form a guide for the slidable serrated jaw, 13, the rear wall of the channel in which said jaw operates being inclined relatively to the base 80 of the jaw holder, 10, and to the face plate 85 to which said holder is secured.

The longitudinal side walls of the channel, 12, are also channeled at 12' and at the base or rear, the sliding jaw is thickened or 90 enlarged transversely to conform to and slidably operate in the channels, 12', said enlargement or thickened portion affording means for boring or otherwise forming a hole, 13; in or longitudinally through this portion, the said base or rear of the sliding 95 jaw being inclined similarly to the inclined plane formed on the bottom or rear wall of the channel, 12, whereby the jaw is accurately guided in its sliding movements.

The front face of the jaw is serrated or 100 provided with teeth as is common in this type of dogs, said front or working face of the jaw being preferably arranged at an angle to the inclined base or rear of said dog and substantially parallel with the face-plate of the lathe.

One end of the channel, 12, in which the serrated jaw slidably operates, is closed by

a cover-plate, 14, to which is secured by any suitable means, a guide rod, 15, and a spring, 16, encircling this rod passes into the bore or hole, 13', of the sliding jaw and is confined between the bottom of this bore and the inner face of the cover-plate, as shown in Fig. 1. One end of the jaw holder, 10, is also channeled in a plane substantially at right-angles to the base line of said holder 10 and to the plane of the face-plate of the lathe and in this channel portion slidably operates a follower or reaction block, 20, having a transverse projection, 21, which extends toward the adjacent edge of the 15 slideable jaw, the face of said projection and the corresponding edge of the sliding jaw being similarly inclined for free sliding movement one on the other, and the body portion of the follower or reaction block 20 being provided with a bore in which is contained a compression coiled spring, 22, the upper portion of which embraces a guide rod, 23, fixed to a plate, 24, which serves as a cover for the outer end of the channel, 25 in which the block operates. The follower or block, 20, is also fixedly secured to or provided with a projecting finger-piece or handle, 25, which extends through a slot, 26, formed in the adjacent wall of the jaw 30 holder, 10, said finger-piece or handle having an opening, 27, through it and having a notch, 28, on its underside leading from said opening. The opening, 27, is adapted to admit a spring latch, 29, one end of which 35 is secured in the jaw holder, 10, while the opposite end is free to work through said opening and to move outwardly and to spring into engagement with said notch, 28, when the finger-piece, 25, has been lifted 40 high enough to allow for this operation.

In order that the present invention may be fully appreciated, it is well to here state that it has been noted under actual working conditions that the serrated sliding jaws 45 of the prior art do not always assume a maximum high position on the inclined planes (dependent upon the magnitude of the cut), and remain there, but work back and forth in the holders on inclined planes, 50 a condition presumably caused by the character of the material being machined, which in the case of steel-tired wheels is likely from the fact that many of them contain segregated hard spots quite frequently 55 termed "nigger heads." It will readily be understood then that the cutting tool when entering one of these hard spots is confronted with an instantaneous increased resistance, which the sliding driving jaw compensates for by automatically assuming a 60 higher position upon the inclined plane, which position is naturally one of greater driving ability, but as this increased resistance to the cutting tool also ceases quite 65 suddenly, a reaction asserts itself and causes

the sliding driving dog to rebound or slide downwardly and away from its maximum high position on the inclined plane, all of which makes for unsteady driving and causes vibration to occur in the machine, 70 greatly reducing the efficiency of the latter. It is to preclude the possibility of this unsteady driving, due largely to backlash or rebound of the sliding driving jaw, that I have devised the present dog, the very nature of which might indicate it as being a 75 non-reaction driving dog.

While I have in the foregoing description identified the dog with a particular form of lathe, and as designed for a particular class of work, I wish it understood that I do not limit the invention to any special form of machine or character of work, neither do I limit said invention to the exact construction and arrangement of parts 80 shown and described, as these are capable of material modifications, which will be within the scope of the invention substantially as hereinafter claimed. In other words, the present invention is believed to 85 be broad enough to comprehend and include any and all means by which the foregoing defects in existing driving-dogs may be obviated, and all reaction or tendency of the dog to rebound or slide downward and away 90 from its maximum high position on the inclined plane when the cutting tool is confronted with instantaneous increased resistance, is avoided. In actual practice one or 95 more of these dogs would be mounted upon 100 each face plate of the machine, the work placed in the lathe and the surface of the work to be driven brought into contact with the serrated driving surface of at least one driving dog, the latch, 29, on the follower 105 or reaction member, 20, released and the lathe started up either at this point or after the latches of the remaining followers or reaction members have been released, all according to convenience of operation and 110 which in driving-wheel-lathe and coach-wheel-lathe operation is usually after the lathe has been started up, as the face plate revolution is quite slow.

From the foregoing it will be evident that 115 as resistance is encountered by the cutting tool, the serrated sliding jaw slides up the inclined plane to a maximum height relative, of course, to the magnitude of the cut or resistance offered to the cutting tool, and 120 the several serrated sliding jaws with which the machine will be provided, are automatically blocked against any backward sliding movement or rebound, from causes as previously described, by the constrained movements of the follower or reaction member, 20, said constrained movement being such that the inclined surfaces, *a*, and *b*, on the reaction member and contiguous edge of the sliding jaw respectively, always contact 125 130

and thereby block the jaw against any backward sliding motion or rebound; at the same time allowing the jaw to readily assume still higher points on the inclined planes, should greater resistance be encountered by the cutting tools and again become automatically blocked against backward sliding motion or rebound.

While I have shown and described a compression coiled spring, 16, acting against the serrated sliding jaw, for the purpose of aiding in maintaining the surfaces, *a* and *b*, in a state of coaction, this spring is not essential for the successful operation of the driving-dog for if this coiled spring were omitted entirely, the co-acting surfaces, *a* and *b*, could readily be dove-tailed each to the other in a state of sliding contact and the action of the driving-dog remains unchanged; or, again, should the coiled spring be omitted entirely the serrated sliding jaw could be brought back by hand each time the follower or reaction member was latched at its highest point relative to the base line, X—Y, of Fig. 1, and the action of the dog will still remain unchanged.

The amount of backward sliding or rebound of the dogs, of the prior art seems to vary with the magnitude of the angle of inclined plane upon which the jaws slide. In the earlier dogs of this type, this inclined plane angle was made only $12\frac{1}{2}$ degrees, with which angle the condition of backward slide or rebound was not so apparent but it soon became quite evident that this angle would have to be increased on account of end-thrust in machine and against wheels due to the action of this type of dog. When it is taken into consideration that the actual pressure developed on each cutting tool in machines of this class approaches 60 tons and that the end-thrust from driving-dogs is in round numbers represented by the product of this 60 tons multiplied by the cotangent of the inclined plane angle, it is at once apparent that the end-thrust was prohibitive and so intense was this end-thrust found to be under actual working conditions that wheels which had been pressed onto axles by hydrostatic means would not hold their positions on the axles against this end-thrust, but continued to slip or be pressed farther on the axle, a condition which cannot be tolerated for one moment. Experiments were, therefore, made and it was found that while dogs constructed upon inclined plane angles as great as 25 degrees would grip with sufficient intensity to drive the work against the cutting tools, the condition of backlash or rebound in the serrated sliding jaws became very noticeable and in some cases prohibitive as the efficiency of the machine was thereby greatly reduced.

It will be noticed, however, in the present illustration that I am using an inclined plane angle of about $22\frac{1}{2}$ degrees and will likely adopt an even greater angle should experiment seem to indicate such an action desirable. In the $22\frac{1}{2}$ degrees arrangement I have by virtue of the new construction with reaction member precluded all possibility of backward sliding or rebound of the serrated sliding jaw, and at the same time I have reduced the former very dangerous and detrimental end-thrust to the irreducible minimum, which minimum will be at the greatest angle of incline plane a driving jaw will grip with sufficient intensity against the work to properly drive the work against the cutting tool.

Having thus described my invention what I claim as new and desire to secure by Letters Patent is:

1. The combination with the sliding jaw of a driving-dog, of means engaging therewith for substantially continuously blocking the jaw against backward motion or rebound.

2. A driving-dog having a slidably-mounted jaw, and means movable in unison with the jaw and engaging said jaw and automatically blocking the same against rebound or return movement.

3. A driving-dog having a movably-mounted jaw adapted to automatically adjust itself in response to an increased resistance to a cutting tool, said dog having means movable in unison with and engaging the jaw and blocking said jaw against rebound or return movement due to a variation in the said cutting tool resistance.

4. The combination with a driving-dog having a gripping jaw constrained to move in a path oblique to the direction of movement of the dog, of means engaging and responding to the movement of the jaw and automatically blocking said jaw against rebound or return movement.

5. The combination with a driving-dog having a slidably-mounted gripping jaw constrained to move in a path oblique to the direction of movement of the dog, of a follower engageable with and responding to the movement of the jaw and blocking the rebound or return movement thereof.

6. The combination with a driving-dog having a gripping jaw constrained to move in a path oblique to the direction of movement of the dog, of a slideable block following the sliding movement of the jaw and adapted to block the rebound or return movement of said jaw.

7. The combination with a driving-dog having a gripping jaw constrained to move in a path oblique to the direction of movement of the dog, of a slideable block following the sliding movement of the jaw and adapted to block the rebound or return

movement of said jaw, and a latch for holding the block at the outer limit of its movement.

8. The combination with a driving-dog 5 having a gripping jaw constrained to move in a path oblique to the direction of movement of the dog, of a slidable block following the sliding movement of the jaw and adapted to block the rebound or return 10 movement of said jaw, a latch for holding the block at the outer limit of its movement, and a compression spring confined between the block and a fixed part of the dog, and operating expansively against the block.

15. 9. The combination with a driving dog having a jaw-holder and a jaw slidably mounted in the holder and movable in a path oblique to the direction of movement of the dog, of a follower backing up the 20 jaw in its gripping movement and blocking a rebound or return movement of said jaw.

10. The combination with a driving dog having a gripping jaw constrained to move in a path oblique to the direction of movement 25 of the dog, of a slidable block following the sliding movement of the jaw and adapted to block the rebound or return movement of said jaw, said jaw and follower having similarly inclined slidably 30 engaged surfaces.

11. A movable work driver comprising a jaw mounted to slide in a path oblique to the direction of movement of the dog, and propelling means for holding the jaw retracted out of engagement with the work but maintaining the jaw free to advance to a higher inclined position in response to increased resistance offered a cutting tool, and means engaging the jaw and continuously 40 blocking the same against rebound or retrograde movement.

12. A movable work driver comprising a jaw mounted to slide in a path oblique to the direction of movement of the dog, and propelling means for holding the jaw retracted out of engagement with the work but maintaining the jaw free to advance to a higher inclined position in response to increased resistance offered a cutting tool, and a follower backing against the jaw and holding 50 said jaw in its advanced position against rebound or retrograde movement.

13. A movable work-driver comprising a jaw-holder and a jaw mounted to slide 55 therein in a path oblique to the direction of movement of the dog, and a propelled follower maintained in contact with the jaw and adapted to advance the same when latent to progressively increasing elevations 60 along its path of movement, and maintain-

ing the jaw blocked against rebound or retrograde movement.

14. A movable work-driver comprising a jaw-holder and a jaw mounted to slide therein in a path oblique to the direction of movement of the dog, and a propelled follower maintained in contact with the jaw and adapted to advance the same when latent to progressively increasing elevations along its path of movement, and maintaining the jaw blocked against rebound or retrograde movement, said jaw and follower having opposed inclined surfaces maintained in 70 slidable contact.

15. A movable work-driver comprising a 75 jaw-holder and a jaw mounted to slide therein in a path oblique to the direction of movement of the dog, a propelled follower maintained in contact with the jaw and adapted to advance the same when latent to 80 progressively increasing elevations along its path of movement, and maintaining the jaw blocked against rebound or retrograde movement, said jaw and follower having opposed inclined surfaces maintained in 85 slidable contact, and latching means for holding the follower in a retracted position.

16. A movable work-driver comprising a jaw-holder and a jaw mounted to slide therein in a path oblique to the direction of 90 movement of the dog, a propelled follower maintained in contact with the jaw and adapted to advance the same to progressively increasing elevations along its path of movement, and maintaining the jaw 95 blocked against rebound or retrograde movement, said jaw and follower having opposed inclined surfaces maintained in slidable contact, a latch for holding the follower in a retracted position, and a compression spring 100 for advancing the follower and in turn moving the jaw along its oblique path, when the latch is released.

17. A movable work-driver comprising a jaw-holder having a guide arranged oblique 105 to the direction of movement of the dog; a serrated jaw slidably mounted on said guide and having an inclined edge; a follower block mounted to slide in the holder in a plane substantially parallel with the axis 110 of the work, and backing against the jaw and having a projection with an inclined face contacting with the inclined edge of the jaw; a compression spring engaged by the block; and a latch for detachably holding the block retracted and with said spring under compression.

In testimony whereof I affix my signature.

SALMON WILDER PUTNAM, 3d.
